UNITED STATES PATENT OFFICE.

EDWARD H. ANGLE, OF NEW LONDON, CONNECTICUT.

ORTHODONTIA APPLIANCE.

1,163,197.

Specification of Letters Patent.

Patented Dec. 7, 1915.

Application filed April 21, 1915. Serial No. 22,778.

To all whom it may concern:

Be it known that I, EDWARD H. ANGLE, a citizen of the United States, and a resident of New London, in the county of New London, State of Connecticut, have invented certain new and useful Improvements in Orthodontia Appliances, of which the following is a specification, reference being had to the accompanying drawings.

10 My invention relates particularly to that class of orthodontia appliances which includes an arch-bow having its terminal portions adjustably engaging with suitable anchorages, and arranged to be connected 15 intermediate of said anchorages with selected teeth of the dental arch, for the purpose of forcing them into normal alinement with the dental arch, and is directed especially to the construction of the terminal anchorages.

20 It has been found in practice, especially in small children, that the tissues of the cheek are very tender and readily irritated by any projecting part of a tooth regulating appliance, such as the free end of the archbow or the tubular sheath of said anchorage.

The principal object of my invention is to provide terminal anchorages for the archbow, which are so formed as to avoid the possibility of any such annoyance to the 30 patient.

Specifically stated, my invention comprehends a terminal anchorage for an arch-bow, having its sheath curved longitudinally to substantially conform to the hollow of the 35 patient's cheek, and tending to direct the terminals of said arch-bow lingually.

My invention also includes all of the various novel features of construction and arrangement hereinafter more definitely specified.

In the accompanying drawings, Figure 1 is an inverted plan view of the upper dental arch, showing a tooth regulating appliance conveniently embodying my invention connected therewith; Fig. 2 is an enlarged fragmentary perspective view of the anchorage shown at the right of Fig. 1; and Fig. 3 is a greatly enlarged fragmentary sectional view of said anchorage, taken longitudinally 50 along the axis of the sheath in a horizontal plane.

In said figures, the dental arch 4 has its lateral incisors 5 and 6 respectively connected by the tooth-bands 7 and 8 with the

arch-bow 9, whose terminal portions 10 and 11 are adjustably engaged with the terminal anchorages 12 and 13, which comprise the anchor-bands 14 and the tubular sheaths 15, through which the terminal portions of the arch-bow 9 extend, and with respect to 60 which said arch-bow may be longitudinally adjusted by the nuts 16.

The anchor-bands 15 may be of any well-known construction arranged to embrace the desired anchor teeth of the dental arch, each 65 being provided with a threaded projection 17 on one end, extended through an eye 19 on the other end, and arranged to be clamped on the anchor tooth by the nut 20, in threaded engagement with said projection 70 17, as shown in Fig. 1.

The sheath 15 which is carried by the anchor-band 14, instead of extending rectilinearly, as heretofore constructed, is bowed longitudinally to substantially conform to 75 the hollow of the cheek of the wearer, so that its distal end tends to curve lingually, whereby any projecting terminal portion of the arch-bow 9 will be directed away from the cheek of the wearer and thereby avoid any 80 possible irritation of the tissues of the cheek.

It will be observed that the terminal portions of the arch-bow 9 may, if desired, be initially curved to conform to the curvature 85 of the sheath 15, so that only a minimum friction between the arch-bow and its sheath may exist, or that the form of said terminal portions may be varied to produce various degrees of frictional co-operation between them and said sheaths, through which they 90 extend; for instance, referring to Fig. 3 of the drawings, the terminal portions of the arch-bow 9 may be initially straight, as shown in dot and dash lines in said figure, or they may be curved, as shown in dash lines 95 in said figure.

It may be here noted that when the terminal portion of the arch-bow 9 is initially curved, as shown in dash lines in Fig. 3, it will when engaged in the sheath 15 tend to 100 shift distally with respect thereto, but when the terminal portion of said arch-bow is initially straight, as shown in dot and dash lines in said figure, any tendency to shift will be mesially effected.

My invention is advantageous in that the sheath tends to curve around the anchor tooth, and therefore more nearly conforms

to the curve of the tooth-band which embraces said tooth, whereby a more perfect union between such a sheath and the band is afforded than when the sheath is straight.

5 I do not desire to limit my invention to the precise details of construction and arrangement herein set forth, as it is obvious that various modifications may be made therein without departing from the essential
10 features of my invention as defined in the appended claim.

Copies of this patent may be obtained for five cents each, by addressing the "Commissioner of Patents, Washington, D. C."

Having thus described my invention, I claim:

An anchorage device for the arch-bow of a tooth regulating appliance, comprising a 15 tooth-band having a curved sheath.

In witness whereof, I have hereunto set my hand this 19th day of April, A. D., 1915.

EDWARD H. ANGLE.

Witnesses:

WILLIAM BELCHER,
NATHAN BELCHER.
